UNITED STATES PATENT OFFICE.

CHARLES ROSS, JR., OF BROOKLYN, NEW YORK.

BELT-SHIFTER.

SPECIFICATION forming part of Letters Patent No. 368,009, dated August 9, 1887.

Application filed April 26, 1887. Serial No. 236,188. (No model.)

To all whom it may concern:

Be it known that I, CHARLES ROSS, Jr., a citizen of the United States, residing at Brooklyn, E. D., in the county of Kings and State 5 of New York, have invented certain new and useful Improvements in Belt-Shifters, of which the following is a specification, reference being had therein to the accompanying drawings, in which—

10 Figure 1 represents a side view of part of a paint-mixer provided with my improvement. Fig. 2 is a vertical transverse section through the line *x x* in Fig. 1; and Fig. 3 shows a plan of my improvement designed to be attached 15 to a machine already built or to be built, or to a machine having a wooden frame.

This improvement relates to a belt-shifter which may be modified so as to be applied to nearly any machine designed to be run by 20 belting passing around fast and loose pulleys; and the invention consists in the peculiar construction, arrangement, and combinations of parts, hereinafter more particularly described, and then definitely pointed out in the claim.

25 Referring to the details of the drawings, which show the preferable plans of carrying out my improvement, A represents the shaft of an ordinary paint-mixer running in suitable bearings, B B', and carrying the bevel-gear C, 30 meshing with a larger bevel-gear, D, set on the vertical shaft of the paint-mixer. Be-

neath the bearing B is a holder, L, cast or otherwise formed or attached to the frame or standard, having a square hole, *b*, adapted to 35 receive a bar, E, which fits in said hole and is held there by a set-screw, F. This bar is shown in Figs. 1 and 2 as bent upward at *e* and as having a horizontal arm, *e'*, substantially at right angles to that part of bar E that enters the hole *b*. On this arm *e'* works a slide, G, preferably provided with a handle, *g*, and having on its under side two holes which receive and hold the ends *h* of the belt guide or yoke H, which ends are securely fastened by 40 means of the nuts I', screwed onto the ends *h* on each side of the slide G, and thus the yoke H is rigidly held in said slide G.

Near each end of the arm *e'* is a pin, J, which acts as a stop to prevent the slide G from traveling too far. The slide is perforated to receive a key, K, which also enters holes I,

formed in the bar E, so that by moving the slide G along the bar E the yoke H is carried over the fast or loose pulley, as may be required, and held there by the key.

55 Where my invention is to be applied to a machine already in use or to a machine having a wooden frame, I prefer to make it in the form shown in Fig. 3, in which the shifter is essentially the same; but instead of the end 60 of the bar E passing into a hole forming part of the machine I use a separate holder, L, provided with holes *l*, through which bolts may be passed to fasten the same to any machine desired.

65 I do not limit myself to the exact construction shown, as it is evident that the form of the holder L may be varied to suit different machines; nor do I limit myself to a square bar, (although I prefer it,) as it is obvious 70 that bars of other forms may be used—as, for instance, a flat bar or a round bar provided with some means for preventing the slide from turning thereon.

I prefer to make two sets of holes I in the 75 arm *e'* at right angles to each other, as shown in Fig. 3, (one set being shown in dotted lines,) in order that the shifter may be more readily adapted to different machines; but this is not necessary where it is designed for some special 80 machine, as one set of holes is all that is required.

The key will prevent the "creeping" of the belt on the tight pulley and the starting of the machine, which frequently occurs with 85 the old style of shifter, to the great danger of the operator.

Instead of the key a set-screw may be used, or a spring-catch that the operator may draw out of a notch on the arm *e'* as he places his 90 hand on the handle *g*.

95 It will be seen that the bar E may be pushed in or out of the holder as desired, and secured by the set-screw to allow larger or smaller pulleys being used, as required, or to suit the angle on which the belt runs. Further adjustments may be had by bending the bar E at different angles or by transposing the slide on the bar, so as to bring the guide or yoke H above or below or on opposite sides of 100 the arm *e'*; or the guide itself may be bent at different angles to suit circumstances. It will

also be seen from the foregoing that my invention makes a very convenient belt-shifter, which can be sold as an article of manufacture, as it is readily adapted to any machine, whether new or old, and one that, while comparatively cheap, will be very durable and not likely to get out of order.

What I claim as new is—

The combination, in a belt-shifter, of the
slide G, the belt-guide H, the holder L, and the

bar E, bent substantially at right angles and having one arm adjustable in said holder, substantially as and for the purpose specified.

In testimony whereof I affix my signature, in presence of two witnesses, this 25th day of 15 April, 1887.

CHARLES ROSS, JR.
